UNITED STATES PATENT OFFICE.

FRANK C. ARMSTEAD, OF BROOKLYN, NEW YORK, ASSIGNOR, BY MESNE ASSIGNMENTS, TO THE WESTINGHOUSE MACHINE COMPANY, OF PITTSBURG, PENNSYLVANIA, A CORPORATION OF PENNSYLVANIA.

FURNACE-GRADE.

SPECIFICATION forming part of Letters Patent No. 746,656, dated December 15, 1903.

Application filed July 23, 1902. Serial No. 116,598. (No model.)

To all whom it may concern:

Be it known that I, FRANK C. ARMSTEAD, a citizen of the United States of America, residing at the city of New York, borough of Brooklyn, county of Kings, in the State of New York, have invented certain new and useful Improvements in Furnace-Grates, of which the following is a specification.

This invention relates to improvements in grates for furnaces of that class known as "inclined" grates or those which consist of a series of transversely-arranged grate-bars having horizontal top surfaces to support the fuel and in which said bars are arranged in stepped relation with the front edge of one bar overlapping the rear edge of the adjacent bar and in which devices are provided for giving a rocking or oscillatory movement to the bars—as illustrated, for instance, in Letters Patent Nos. 409,304, 409,305, and 409,650, granted to William R. Roney on the 20th day of August, 1889.

The invention consists in the features hereinafter described and more particularly pointed out in the appended claims.

As illustrated in the accompanying drawings, Figure 1 is a longitudinal vertical section through the front part of a furnace and a grate therein. Fig. 2 is a face view of one of the grate-bars shown in Fig. 1. Fig. 3 is a plan view of the grate-bar shown in Fig. 2. Fig. 4 is a detail cross-section taken through two adjacent grate-bars on the line indicated by 4-4 of Fig. 2, the said grate-bars being shown at an intermediate position of their oscillatory movement. Fig. 5 is a sectional view similar to Fig. 4, showing the relative position of the two bars when at the extreme limit of their throw in one direction. Fig. 6 is a like view showing the same bars at the extreme limit of their throw in the opposite direction. Fig. 7 is a sectional view taken on line 7-7 of Fig. 2. Fig. 8 is a detail longitudinal section of the grate-bars shown in Figs. 2 and 3, taken on line 8-8 of Fig. 3. Fig. 9 is a longitudinal section taken on line 9-9 of Fig. 3. Fig. 10 is a sectional view of two grate-bars, generally like those shown in Figs. 1 to 9, but differing somewhat in the form of the rear edges of the bars. Fig. 11 is a sec-

tional view taken on line 11-11 of Fig. 10, showing the rear part of the lowermost member in longitudinal section and the front edge of the uppermost bar in front elevation. Fig. 12 is a sectional view of two bars differing from those shown in the preceding figures in respect to the shape of the fuel-supporting surfaces of the bars. Fig. 13 is a like section of two bars, showing still another modification of the form thereof. Fig. 14 is a detail view showing in front elevation the outer edge of one of the bars illustrated in Fig. 13.

First referring briefly to the general illustration given in Fig. 1, A indicates the front wall of a furnace, and B the dead-plate or plate located at the bottom of the fuel-door of the furnace over which the fuel passes to the top of the grate. C indicates one of the inclined side bearers by which the bars constituting the inclined grate are sustained or supported. D D D indicate the grate-bars, which are arranged in stepped order with the rear edge of each bar overhanging the front edge portion of the next bar below it, so as to give an inclined form to the grate as a whole. E indicates an inclined actuating-bar through the medium of which oscillatory movement is given to the several grate-bars. Each grate-bar D is provided at its ends with trunnions d d, which rest in bearing-notches formed in the inclined supporting plates or bearers, one of which is indicated by C. Each of the bars D consists of two main portions—viz., a relatively thin vertically-arranged lower member or web D' and a top plate D², which is secured upon the upper edge of the web and which forms the fuel-supporting surface of the bar. The web D' is shown as made of skeleton form in order to reduce the weight of the bar and to facilitate the passage of air therethrough to the fire and to permit the introduction of a slicing-bar when necessary. The trunnions d d are cast upon or made integral with the ends of said web. Said web is, moreover, provided at its upper edge with a plurality of elevated bearing projections or lugs d' d', which form seats to receive depending bosses d², formed on the lower surface of the top plate D². Said web is shown as provided with bolt-holes 100

through which are inserted bolts d^3 , which pass through vertical apertures in the top plate and in said lugs d^1 and which serve to detachably secure said top plate to the web. 5 The said web D' is also shown as provided with a depending arm or lug d^4 , which is adapted to engage one of a series of notches e in the actuating-bar E , whereby endwise reciprocatory motion in the said actuating-bar is transmitted to the several grate-bars for giving oscillatory or rocking movement thereto. E' in Fig. 1 indicates an operating bar or pitman by which motion is transmitted from suitable grate-actuating devices to the 15 actuating-bar E , said pitman E' being pivoted to the bar E by a pivot-pin e' . In the case of a number of bars at the upper part of the grate the notches e are preferably made wider than the ends of the arms d^4 , which engage 20 the same, while in the case of the bars at the lower part of the grate the said notches e are made about as wide as or only slightly wider than the ends of said arms d^4 , this construction affording considerable lost motion between 25 the actuating-bar and the grate-bars at the lower part of the grate, so that the latter are oscillated through a less distance than the bars at the lower part of the grate. This prevents a too-rapid movement of the fresh 30 or unburned fuel at the top of the grate, which is liable to move more freely than that which has been partially burned.

So far as above described the grate-bars illustrated in the drawings are generally similar to those shown in the prior patents granted to William R. Roney, hereinbefore referred to, and in a prior patent, No. 581,061, granted to William W. Churchill April 20, 1897.

40 The features constituting my invention are embodied in the upper members or top plates of the grate-bars or the portions thereof upon which rests and by which is supported the fuel, which is delivered to the upper end of 45 the inclined grate and which is carried or moved downwardly over the grate-bars through the rocking or oscillatory movement given thereto during the process of combustion.

50 First referring to the form of construction in the top plate or upper member D^2 of the grate-bar, which is illustrated in Figs. 1 to 9, inclusive, the grate-bar is elevated at its inner and outer margins above its intermediate 55 portion, or, in other words, is curved transversely, so as to give to its fuel-supporting surface a concave or recessed form, and is also provided with transverse ridges, the transversely-curved form of the plate forming between the said ridges a series of cavities, depressions, or pockets. As shown in 60 Figs. 2, 4, 5, 6, 7, 8, and 9, the ridges and depressions referred to are formed by transversely corrugating the plate, so as to constitute alternate grooves and ridges on both the upper and lower surfaces thereof. Moreover, 65 as shown in said figures, the front edges of

the said top plates are corrugated to correspond substantially with like corrugations on the rear edge of said top plate, while at 70 the intermediate portion of the bar or that which constitutes the fuel-supporting surface thereof the corrugations are made of considerably greater depth, as more clearly shown in Figs. 4, 5, and 6 and in dotted lines in Fig. 75 2, thereby forming a plurality of depressions or pockets between the transverse ridges, the same being arranged at equal intervals across the fuel-supporting portion of the bar or that part of the same which is not covered by the 80 overlapping front margin of the next bar above it. As shown in the figures above referred to, the transverse ridges (indicated by d^5) are straight, or approximately so, on their upper surfaces, while the bottoms of the intervening depressions are elevated at their rear parts, as indicated by d^6 , and are also elevated at their forward parts, as indicated by d^7 , but are depressed in their parts indicated by d^8 to form the recesses or pockets hereinbefore referred to. The bars having their upper members or top plates shaped as above described are so arranged in the furnace that the transverse ridges and intervening depressions of the several bars come in the same vertical 95 planes, so that the ridges and depressions at the forward edge of one bar correspond in position with and are adapted to fit into the ridges and depressions at the rear edges of the subjacent bar. As a result of this construction when the bars are rocked or moved in a direction to carry their forward edges downwardly and their rear or inner edges upwardly the depending projections on the uppermost bars fit or enter within the depressions of the under or lowermost bars. As 100 illustrated in the accompanying drawings, Fig. 4 shows the two adjacent bars in an intermediate position of their throw, Fig. 5 shows the same bars with their outer or fuel-supporting margins thrown downwardly and the said margins in contact, or substantially so, with the rear margins of the subjacent bars, and Fig. 6 shows the position of the adjacent bars when the fuel-supporting margins are 105 thrown upwardly and the bars are most widely separated from each other. As shown in said 110 Figs. 1 to 9, inclusive, the upper members or top plates of the grate-bars are provided with air passages or openings extending vertically therethrough and located in transverse rows along the elevation or ridges of the bars, these openings, as clearly seen in Fig. 7, being preferably made of tapered form and larger at their lower than at their upper ends. 115 Said air passages or openings (indicated by d^9) are for the purpose of admitting a supply of air to the fuel in excess of or additional to that furnished through the spaces between the overlapping edges of the bars.

120 An important feature of the grate-bar made as above described is the concaved or recessed form given to the upper or fuel-supporting surface of the bar. One important advantage

- gained by the recessed or concaved form of the top surface of the bars is that of retaining on the bars layers or masses of ashes from the burning fuel, which ashes by reason of the depression of the bottoms of the recessed parts or pockets of the bars below the forward edges thereof are confined in the said recessed parts or pockets and therein remain, notwithstanding the vibratory movement of the bars.
- 5 10 The masses of ashes thus lodged on the bars largely prevent immediate contact of the burning fuel with the surface of the bars, and thus greatly facilitates the keeping of the same cool, or, in other words, decreases the liability of the burning out of the bars. Another advantage gained by the presence of said concave parts or depressions is that of retarding the downward movement of the fuel along or over the stepped surface of the inclined grate,
- 15 20 especially in the case of fine or granular anthracite coal, it being obvious that the downwardly-moving particles of the coal are more liable to be arrested and temporarily held from downward movement by contact with the concave or depressed parts of the grate-bars than in the case of a bar having a flat or substantially flat top surface.

An important advantage is gained by the presence of the air-openings ^{d¹}, arranged along 30 the elevated parts or ridges of a grate-bar having such ridges, for the reason that these openings not only afford an additional supply of air to the fuel, but because the air is supplied at points between the cavities or recesses, so that the entering air will have no tendency to disturb the masses of ashes lodged in said cavities, while at the same time the air entering through the holes in the ridges tends to keep the metal cool along the ridges 35 40 and lessens the liability of injury through direct contact of the burning or incandescent fuel with the metal, which at these points is unprotected by the masses of ashes.

A general advantage gained by making the 45 grate-bars of laterally-curved or channel form, as well as by corrugating them transversely, is that a bar of this shape is stronger or stiffer and is less liable to be warped or distorted by heat than would be a straight bar 50 containing the same weight of metal. It will be especially observed that inasmuch as the front edge of the bar, which directly supports and is most directly exposed to the heat from the incandescent fuel, is liable in the case of 55 a straight bar to be expanded by heat, so as to bend the bar into concave form at its rear edge, while in the case of a bar corrugated at its front edge in the manner shown the action of the heat has no tendency to expand 60 or elongate said front edge of the bar. Moreover, in a form of bar in which the corrugations extend entirely across the width of the bar, as is the case in the construction shown in Figs. 1 to 9, practically no endwise expansion 65 of the bar will take place under the action of heat, it being of course seen that such endwise expansion would be objection-

able, because the top plate being secured to the lower part or web of the bar the greater expansion of the said top plate under the 70 greater heat to which it is subjected would result in the warping or bulging of the top plate and in the liability of distortion of the entire bar.

An important general advantage gained by 75 the use of a transversely-corrugated top plate is that the corrugated form of top plate affords a much larger area of heat-radiating surface, and therefore parts with its heat much more rapidly than would a flat bar. 80 As a consequence the transversely-corrugated top plate described has much greater durability under the action of the burning fuel than does a flat bar.

An advantage gained by corrugating transversely the rear or inner, as well as the forward or outer, edges of the bars and so arranging the bars that the ridges and grooves of adjacent bars fit within each other is that this construction affords a greater degree of 90 oscillatory movement in the bars than would be possible if the front edges of the bars were corrugated and the top surfaces of the bars at their rear edges were straight or flat, because in the latter case the ridges on the lower 95 surfaces of the front edges of the superposed bars would strike the flat rear edges of the subjacent bars, and thereby limit the movement of both bars. Such greater amplitude of vibratory movement is desirable, because 100 giving greater agitation of the fuel, such as is especially desirable in the case of fuels which are liable to coke or cake in the process of combustion. The corrugation of the upper surface of the rear margins of the bars 105 to fit the corrugations of the lower surface of the front margins of the bars is also an advantage, because making it possible to limit to a desired extent the passage of air between the bars, it being obvious that if the actuating 110 devices for the bars thus constructed are so adjusted as to bring the edges of the bars together the passage of air through the bars at the time they are oscillated forwardly or downwardly will be entirely cut off and in 115 other positions correspondingly lessened.

This is a matter of considerable importance in the use of fine coal and where a strong draft is present, and especially in the use of a blower or forced draft, for the reason that 120 if wide openings are afforded between the bars the air may pass therethrough with such force and volume, especially at the upper part of the grate, as to dislodge from the grate-bars the fine fuel resting thereon. In this 125 connection it is to be noted that the provision of air-openings ^{d¹} along the ridges of the grate-bars is of importance, because in the use of fine fuel, which is liable to be dislodged by the entrance of air-currents of considerable 130 force and volume, by making the contact-surfaces of the bars of corrugated form and in such manner that they interfit when brought into contact with each other and at the same

time providing said air-openings the air-supply will be largely afforded by said openings d^9 , which direct small jets of air upwardly through the fuel, which jets of air deflect upwardly the air entering horizontally between the bars, and thereby afford a suitable air-supply with much less liability of dislodging the fine fuel than in the case when all of the air enters horizontally between the grate-bars.

Figs. 10 and 11 illustrate a construction in the meeting edges of adjacent grate-bars in which both the forward edge of the upper bar and rear edge of the lower bar are corrugated, but in which the corrugations in one part are deeper than those in the other, so that when the overlapping margins are brought together in the rocking of the bars spaces or openings are still afforded for the passage of air. A construction of this kind will of course be employed in cases where the entrance of air with considerable force and volume between the grate-bars will not be objectionable, it being obvious that this construction will make it impossible for the operator to so adjust the actuating devices of the bars as to entirely close the spaces between the bars, and thus cut off the supply of air in any position of said bars.

In Fig. 12 is shown a construction slightly different from that illustrated in Figs. 1 to 9 by reason of the fact that the transverse ridges of the corrugated top plate (indicated by d^{10} in said Fig. 12) are curved to conform to the curvature of the bottom of the depressions or recesses between the ridges instead of being straight, as shown, for instance, in Fig. 4.

In Figs. 13 and 14 I have shown a form of grate-bar embodying the main features of my invention wherein the fuel-supporting surface only of the bar is corrugated, while the rear surface of the bar or top plate, which extends beneath the front margin of the superjacent bar, is flat or uncorrugated. The advantages gained by the provision of depressions or recesses to receive and hold ashes and the benefits derived from giving a corrugated form to the part of the bar most greatly exposed to the heat are the same in this form of bar as in the form of construction hereinbefore described.

An advantage arising from the use of the construction shown in Figs. 1 to 9, as compared with the prior flat form of top plate will be obvious from consideration of the fact that as the forward edge of the upper bar approaches the flat surface of the lower bar, these surfaces being approximately parallel with each other, some of the fine fuel which may have fallen on the rear surface of the lower bar may be squeezed or forced out of the space between the bars, and thus fall through the grate. When, however, the bar is concave and its lower surface is inclined upwardly toward the front edge of the bar, as shown in Figs. 4, 5, and 6, the rear edge of the lower bar will strike the under

surface of the upper bar at the depressed part of said surface, so that a V-shaped opening, Fig. 5, will be left between the adjacent surfaces of the bars, and any fuel caught between the bars will be forced forwardly upon the lower bar and will have no tendency to fall through the space between the bars.

It is to be understood that my invention is not limited to the specific details of construction shown in the accompanying drawings, but that such details may be varied in the practical carrying out of my invention, as may be found necessary or desirable. It is also to be understood that the features specifically pointed out in the several claims are intended to be separately claimed without limitation to the use in connection therewith of other features and details of construction illustrated.

I claim as my invention—

1. An inclined grate consisting of a plurality of pivotally-mounted grate-bars arranged in stepped and overlapped relation, the upper surfaces of said bars being provided with transverse ridges and the bottoms of the grooves between the said ridges being elevated at the outer and inner margins of the bar to form pockets which constitute ash-receiving recesses.

2. A grate having a plurality of pivotally-mounted overlapping grate-bars, the upper surfaces of said bars, in their fuel-supporting portions, being provided with transverse ridges and the bottoms of the grooves between said ridges being elevated at the outer and inner margins of the bars and the depressed part of said grooves extending throughout the greater portion of the width of the said fuel-supporting part of the bar to form transversely-elongated pockets which constitute ash-receiving recesses.

3. A grate provided with a plurality of pivotally-mounted, overlapping grate-bars provided on their top surfaces with transverse ridges extending throughout the width thereof, the bottoms of the grooves between said ridges being elevated at the outer and inner margins of the fuel-supporting portion of the bars to form pockets constituting ash-receiving recesses.

4. A grate having a plurality of pivotally-mounted, overlapping grate-bars provided on their upper surfaces with transverse ridges, the bottoms of the grooves between said ridges being elevated at the outer and inner margins of the bars to form pockets which constitute ash-receiving recesses, said bars having air-supply openings extending through the said ridges.

5. An inclined grate consisting of pivotally-mounted overlapping grate-bars arranged in stepped relation, and provided on their upper surfaces with transverse corrugations, forming ridges and intervening grooves, the bottoms of which were elevated at the outer and inner margins of the bars to form pockets which constitute ash-receiving recesses be-

tween the ridges, the lower surfaces of the bars, at their outer edges, being corrugated to correspond with the corrugations at the top surface of the bars and the grooves in the 5 upper surfaces of the bars at the inner edges thereof being deeper than the ridges on the lower surfaces of the superposed bars at the outer edges of the latter.

6. An inclined grate consisting of pivotally-mounted, overlapping grate-bars arranged in stepped relation and having top plates which are transversely corrugated, the bottoms of the grooves formed by the corrugations in the top surfaces of the bars being elevated at the 10 outer and inner margins of the bars to form pockets which constitute ash-receiving recesses.

7. A top plate or member for a grate-bar, which is transversely corrugated, and in 15 which the bottoms of the grooves in the cor-

rugated top surface of the plate are elevated at the side edges of the bar to form pockets which constitute ash-receiving recesses.

8. A top plate or member for a grate-bar, which is transversely corrugated throughout 25 its width, the bottoms of the grooves formed by the corrugations in the top surfaces of its fuel-supporting portion being elevated at the outer and inner margins of said fuel-supporting portion to form pockets which constitute 30 ash-receiving recesses.

In testimony whereof I have signed my name to this specification, in the presence of two subscribing witnesses, this 10th day of July, 1902.

FRANK C. ARMSTEAD.
